UNITED STATES PATENT OFFICE.

IRA E. SMITH, OF STOCKTON, CALIFORNIA.

INITIAL FUEL-OIL HEATING MEANS.

Application filed May 25, 1926. Serial No. 111,622.

This invention relates to improvements in means for heating fuel oil and especially for heating the oil of the grades used in connection with the more or less sensitive motor 5 driven and similar oil burners.

At present the oil is usually heated before being delivered to the burner but the heating means is regulated by a definite temperature only. In other words such heating means 10 operate to merely insure that the oil when delivered to the burner will be at a certain relatively high temperature.

If all the oil supplied to a certain burner could be depended upon as being of a constant viscosity, this method would be satisfactory. In practice, however, I have found 15 that the oil delivered to the consumer from day to day by the oil companies, while presumably being of the same grade, varies considerably in viscosity. Therefore if a relatively heavy oil is merely raised to a temperature of say 150 degrees, its viscosity at such temperature will still be greater than the viscosity of a naturally lighter oil raised 20 to the same temperature, as will be evident. The result is that it is almost impossible to set the smaller sensitive burner regulating valves at any definite point, since at one time a somewhat heavy oil is passing there- 25 through and at another time a lighter oil is passing through the valve. This necessi- 30 tates constant adjustment of the valve by the operator to insure uniform and proper operation of the burner.

The principal object of my invention therefore is to provide a system or apparatus for initially heating the fuel oil, in which the heating means is controlled not by any certain temperature but by the viscosity of 35 the oil itself after it has passed through the heating medium. The apparatus is arranged in such a way that regardless of the viscosity of the oil initially fed to the heating means, said oil as it leaves the heating means will 40 be of a uniform viscosity. To accomplish this a heavy oil will naturally have to be raised to a higher temperature before it attains a viscosity equal to that of a thinner oil, but with my apparatus the temperature 45 attained by the oil is incidental and does not of itself control the operation of the heating means.

The result therefore of the use of my apparatus in connection with an oil burner 50 is that the oil as fed to the burner is always of a uniform viscosity, which viscosity is

capable of being regulated to suit, and with the operation of the apparatus such viscosity is automatically maintained without any attention at all on the part of an attendant 60 being necessary.

A further object of the invention is to produce a simple and inexpensive apparatus and yet one which will be exceedingly effective for the purpose for which it is designed. 65

These objects I accomplish by means of such structure and relative arrangement of parts as will fully appear by a perusal of the following specification and claims.

In the drawings similar characters of 70 reference indicate corresponding parts in the several views:

Fig. 1 is a diagrammatic view of my oil heating system showing steam as the heating medium and an electrically actuated valve 75 for the steam line.

Fig. 2 is a sectional elevation of the oil pressure-actuated diaphragm structure.

Fig. 3 is a fragmentary view showing the steam valve and a direct connection between 80 said valve and the diaphragm stem.

Fig. 4 is a fragmentary diagrammatic view showing the heating means as being electricity, and also showing the control means for the circuit of the heating means 85 as being directly controlled by the dia- phragm stem.

Fig. 5 is a fragmentary diagrammatic modification of the apparatus showing the heating means as being gas or fuel oil. 90

Referring now more particularly to the characters of reference on the drawings, and particularly at present to Figs. 1 and 2, A represents the boiler or furnace to be heated by a burner B of any suitable character, and C represents the main tank for the fuel oil to be supplied to the burner. 95

My heating means arranged in connection with these parts comprises an oil pipe line 1 leading from the tank C to a relatively 100 small reservoir or tank 2, from the bottom of which tank a pipe line 3 leads to the burner B. The cold oil being pumped into the top of the tank and the hot oil taken out of the bottom, causes a substantially uniform tem- 105 perature of oil in said tank to be maintained, since the oil as it is heated tends to rise, and intermingles with the downwardly moving cold oil.

Interposed in the pipe line 1 is a pump 4 110 of a constant flow type, such as a rotary or gear pump of common character. This pump

is driven at a suitable and constant speed so as to deliver a certain number of gallons per minute, regardless of the viscosity of the oil passing through the pump by means of an 5 electric motor 5. A burner controlling valve V is interposed in the pipe line 3 adjacent the burner to control the flow of oil to the burner, and to enable a pressure being maintained in the pipe line ahead of the valve.

10 A steam line 6 leads from the boiler to the tank 2 and passes through the tank from top to bottom in the form of a coil 7. A valve 8 preferably of the needle type is interposed in the steam line 6, the stem 9 of 15 the valve being connected to the lower end of an armature 10. This armature is pivoted intermediate its ends in connection with an electromagnet 11, the opening and closing of the circuit wires 12 of said electromagnet 20 being controlled as hereinafter seen. The arrangement of parts of this device is such that when the electromagnet is deenergized the steam valve will be closed.

Interposed in the pipe line 3 is a hollow 25 member 13, one side of which, between the connection of the pipes 3 therewith, is formed as a diaphragm 14 expanded by pressure. An adjustable compression spring 14^a bears down on the diaphragm so that the 30 pressure thereunder and necessary to expand the same may be varied to suit. Removably fitted in the member 13 adjacent the outlet pipe 3, and beyond the corresponding end of the diaphragm is a plug 15 having a passage 35 16 therethrough which is very restricted in size compared to the interior area of the member 13 or the pipes 3. This plug is made removable so that plugs having different sized passages may be inserted therein, depending upon the viscosity and quantity of 40 the oil which it is desired to be fed to the burner. This plug is made of hardened steel so that the oil when being forced therethrough will not tend to wear the hole large 45 and thus destroy its accuracy of regulation. A stem 17 projects upwardly from the diaphragm 14 and is connected at its upper end in offset relation to the pivot 18 of a mercury-tube switch contact device 19. As customary 50 in devices of this character the contacts project into the tube in spaced relation adjacent one end of the same, the tube being arranged so that when the diaphragm is in its normal unexpanded condition, which is when 55 there is a lack of pressure in the member 13 sufficient to expand the same, the tube is then at an angle such that the mercury is not engaged with the contacts 20, or in other words the switch is open. The contacts 20 are interposed in the circuit wires 12 of the 60 electromagnet 11, so that when the tube is in the above named position the circuit to said electro-magnet will be broken.

From a point between the pump 4 and the 65 tank 2 a bypass pipe line 21 is connected to

the pipe line 1 which leads back to the tank C. A relief valve 22 of suitable adjustable character and opening only toward the tank C is interposed in said pipe line 21. Between the discharge side of the member 13 70 and the burner B a bypass or return pipe line 23 is connected to the pipe line 3 and leads to the suction side of the pipe line 1 or direct to the tank C, as may be desired. A relief valve 24, of a character similar to the valve 22 but having a lesser resistance is interposed in the pipe line 23, this valve opening only away from the pipe line 3. A pressure gage 25 of suitable character is interposed in the pipe line 1 beyond the pump and a similar 80 gage 26 is interposed in the pipe line 3 beyond the member 13.

The relief valve 22 is set to open with a higher pressure than that causing the valve 24 to open and the capacity of the pump is 85 greater than that of the burner B, so that a pressure will always be maintained in the pipe lines.

The operation of the apparatus is as follows:

The oil is drawn from the tank C by the operation of the pump 4 which pumps a constant flow or volume per minute into the pipe line 1 beyond the pump and ahead of the return pipe 21. The same volume of oil 95 is also delivered to the tank 2 unless the pressure in the pipe line 1 exceeds the pressure necessary to open the valve 22, when sufficient oil to relieve this excessive pressure returns to the tank C or pipe line 1 100 through pipe 21. Upon reaching the discharge side of the member 13 the outflow of the oil is very much restricted owing to the presence of the small passage 16 through which all the oil from tank 2 must pass before it can reach the burner. If the viscosity of the oil is high, greater resistance to the flow of the oil through said small passage will of course be had than if the viscosity of the oil is relatively low. The 110 result is that varying pressures are built up within the member 13, depending on the viscosity of the oil as above stated, and upon the setting of the relief valve 22. When this pressure has reached a predetermined 115 amount, depending on the setting of the diaphragm spring, the diaphragm 14 will be expanded and raised. The diaphragm spring must of course be set so that the diaphragm will operate with a pressure less 120 than that necessary to open the valve 22. This raising of the diaphragm raises the stem 17, turns the switch tube 19 on its pivot so that the mercury engages the contacts 20, and the circuit 12 will be closed 125 and the electro-magnet 11 energized. This will cause the armature 10 to be drawn to said electro-magnet, opening the steam valve 8 and allowing a flow of steam to pass from the boiler to the coils 7 in the tank 2. The 130

oil passing through the tank will therefore be immediately subjected to the heat of the coils 7, with the result that very shortly the pressure accumulating in the member 13 will be reduced to such an extent that the diaphragm 14 will no longer be expanded. This is on account of the fact that as the oil becomes heated it thins out or loses a certain viscosity, and therefore such oil can 10 more readily pass through the passage 16, and the oil pressure in the member 13 is lessened. As the diaphragm resumes its normal position the switch member 19 is opened, the electromagnet is deenergized, and the 15 steam valve closes. The parts will remain in these positions until with the cooling off of the coils 7 the oil passing thereby will rise in viscosity, again causing the pressure in the member 13 to be built up and the diaphragm 14 again expanded. It will therefore be seen that the functioning of the parts will continue automatically as long as the entire system is in operation. The passage 16 in the member 15 is of such a size 25 that the pressure accumulating in the member 13 before the diaphragm 14 is expanded must reach a predetermined amount, and by altering the size of this passage, the ultimate viscosity and quantity of the oil passing to the burner may be regulated to suit 30 different conditions.

By adjusting the valve 22 one way or the other, more or less oil may pass to the heater without being bypassed back to the tank 35 or pump. This results in an increase or decrease in pressure against the diaphragm, causing the heat to be kept on for a longer or shorter time, with the same diaphragm-spring adjustment, and the viscosity of the 40 oil finally delivered to the burner is altered accordingly.

The valve 24 in return pipe 23, which is set to open at a lower pressure than valve 22 but the same as the pressure desired to be 45 delivered to the burner allows some of the oil to return to pipe line 1 (or tank C), since as before stated, the capacity of the pump is greater than that of the burner, and all oil fed to the pipe line 3 beyond the diaphragm member will not be utilized. By 50 reason of the various adjustment features, it will be seen that independent of the initial viscosity of the oil, the viscosity of said oil as delivered to the burner may be varied 55 to suit different conditions.

Neither one relief valve nor the other is sufficient to take care of the needs of the system but both must be used, since both necessarily operate at different pressures.

60 If the pipe 23 led back to the tank C (as would be done in cold climates) all the oil in the system would sooner or later be heated, since some oil is continually passing through the pipe 23.

65 The mercury tube switch is also construct-

ed so as to enable its slope to be adjusted, so that the extent of expanding movement of the diaphragm, independent of the spring acting thereon, may be adjusted to suit. As above described, electrical control means 70 is used for the steam valve. This I feel to be the best for the purpose as being the most sensitive and quick acting. If desired, however, the diaphragm stem 17^a could be connected directly to the stem 9^a of the steam 75 valve 8^a by means of a lever 27 interposed between the stems as shown in Figure 3.

In the apparatus above described steam is shown as being the heating means. This necessitates of course that the oil burner 80 operate for a certain length of time before any steam is generated in the boiler, so that when first firing up the oil in its heavy condition must be burned without being heated 85 or thinned out.

To avoid the necessity of this heavy oil passing through the passage 16, I provide a bypass passage member as at 3^a providing communication between member 13 ahead of the passage 16 and the pipe 3 beyond said 90 passage, with a normally closed hand operated valve P in said bypass passage.

In Fig. 4 therefore I have shown how the oil may be electrically heated without depending upon steam. In this arrangement 95 the tank 2 has electrical heating elements 28 therein, said elements of course being insulated from the oil passing through the tank 2^a. The circuit wires 29 of these heating elements are connected directly to the 100 contacts 20^a of the mercury tube switch 19^a, which switch is actuated in the same manner as the switch 19 first described.

Gas or other heating means may also be 105 used to initially heat the oil. I have shown such an arrangement in Fig. 5, in which the tank 2^b forms merely a firebox or enclosure for an ordinary gas burner 30. In this case the oil pipe line 1^a passes through the tank 2^b in the form of a coil 31 disposed above the 110 burner, so that the oil flowing through the coil will be subjected to the heat of the burner 30. The gas supply pipe 32 leading to the burner 30 has a valve 33 therein, which is opened and closed by a connection 115 with the stem 17^b of the diaphragm structure in the same manner as was shown in connection with the steam valve in Fig. 3. It will be obvious however that regardless of the type of heating means the operation of 120 the system will be the same in any case, and will be as efficient with one kind of heat as with another.

From the foregoing description it will be 125 readily seen that I have produced such an apparatus as substantially fulfills the objects of the invention as set forth herein.

While this specification sets forth in detail the present and preferred construction 130 of the apparatus, still in practice such devia-

tions from such detail may be resorted to as do not form a departure from the spirit of the invention, as defined by the appended claims.

5 Having thus described my invention what I claim as new and useful and desire to secure by Letters Patent is:

1. In combination with a source of supply, an oil pipe line leading therefrom, means 10 for heating the oil as it passes through the line, a pump interposed in the line ahead of the heating means, a return pipe leading from the line between the heating means and pump to the source of supply, an adjustable 15 relief valve in the return pipe opening away from the heating means, a restricted passage in the line beyond the heating means, a valve in the line beyond said passage, a return pipe from the pipe line between the 20 valve and passage to the line ahead of the pump, and an adjustable relief valve in said return pipe opening away from said other valve.

2. In combination with an oil pipe line 25 leading to a point of consumption, means for heating the oil as it passes through the line, means for forcing the oil to the heating means with a constant volumetric flow, means for regulating the pressure of such 30 flow as delivered to the heating means, means interposed in the line beyond the heating means and actuated by the viscosity

of the oil in the line for controlling the operation of the heating means, and means connected to the line between the viscosity 35 actuated means and the point of consumption for regulating the pressure of oil delivered to the point of consumption independent of the pressure of the oil in the pipe line ahead of the heating means. 40

3. In combination with an oil pipe line leading to a point of consumption, means for heating the oil as it passes through the line, means for forcing the oil to the heating means with a constant volumetric flow, 45 means for regulating the pressure of such flow as delivered to the heating means, means interposed in the line beyond the heating means and actuated by the viscosity of the oil in the line for controlling the 50 operation of the heating means, and means connected to the line between the viscosity actuated means and the point of consumption for enabling the oil passing through the line beyond said viscosity actuated means 55 to be maintained at a constant pressure irrespective of the initial pressure, and regardless of any lowering of viscosity.

4. A structure as in claim 3 with means incorporated in connection with said constant pressure maintaining means for altering such constant pressure. 60

In testimony whereof I affix my signature.
IRA E. SMITH.
